LATCH FOR MAIL BOXES OR THE LIKE

Filed April 14, 1924

Patented Feb. 17, 1925.

1,526,763

UNITED STATES PATENT OFFICE.

FERDINAND SCHWARZ, OF SHEBOYGAN, WISCONSIN.

LATCH FOR MAIL BOXES OR THE LIKE.

Application filed April 14, 1924. Serial No. 706,487.

To all whom it may concern:

Be it known that I, FERDINAND SCHWARZ, a citizen of the United States, and resident of Sheboygan, in the county of Sheboygan and State of Wisconsin, have invented certain new and useful Improvements in Latches for Mail Boxes or the like; and I do hereby declare that the following is a full, clear, and exact description thereof.

10 This invention relates to mail boxes.

Objects of this invention are to provide a mail box which is so constructed that a latch is provided and associated with the box as a unitary structure, in which the latch and 15 the door to the mail box are so related that manipulation of the latch, that is, moving it to unlocking position automatically throws the door open, and in which the mere closing 20 of the door automatically throws the latch into locking position.

Further objects are to provide a mail box which consists of a minimum number of parts, which is so constructed that rain is prevented from entering, and which may be 25 cheaply and readily manufactured.

An embodiment of the invention is shown in the accompanying drawings, in which:—

Figure 1 is a side elevation partly broken away showing the box in closed position.

30 Figure 2 is a similar view showing the box open.

Figure 3 is a plan view of the structure shown in Figure 1.

The box comprises a main compartment 35 formed of an upper and side member which is of generally arched formation, as indicated at 1, and which is provided with downwardly turned lower flanged portions 2 adapted to be secured by nailing or other 40 suitable means to a support 3. Obviously, the box could be attached to the support by nailing or otherwise securing the device through the flat bottom portion 4.

45 A door 5 of the same general contour as the cross-sectional contour of the box is provided and is equipped with marginal flanges 6, the lower ends of which are connected by means of a pintle 7 with the body of the box. It is to be noted that the support 3 is 50 stopped short of the overhanging edge 4' of the bottom, as may be seen from Figures 1 and 2, and that this overhanging portion constitutes a stop for the door, as shown in Figure 2, thus holding the door in horizontal 55 position when it is open. It is to be noted that the flanges 6 are inturned, as indicated

at 6' in Figure 2, to provide a channel like portion adapted to receive the outer edge of the body part 1 of the box.

The upper portion of the box adjacent its front end is provided with a plate or similar member 8 equipped with upstanding lugs 9. A shield 10 extends upwardly and forwardly over the rear and a portion of the upper curved part of these lugs 9. The latch comprises a body portion 11 which is fitted between the lugs 9 and is pivotally secured thereto by means of a pintle or pivot pin 12. This body portion is provided with a rearwardly extending arm 13 terminating in a hook or stop 14 which in closed position lies beneath the upper edge of the body of the box, as shown in Figure 1. This body portion also has a forwardly extending neck portion 15 to which a relatively massive weight 16 is integrally secured. This weight is provided with an inwardly directed projection or tongue 17 which normally engages the door 5 when in closed position, as shown in Figure 1, and thus locks the door against forward motion.

When it is desired to unlatch and open the box, it is merely necessary for the operator to grasp the weight 16, which in itself constitutes a handle, and rock this weight rearwardly into the position shown in Figure 2. Under these conditions the latching tongue 17 is moved out of engagement with the front of the door 5 and the projection 14, upon continued motion of the latch, strikes the inner portion of the door and rocks the door outwardly into open position.

When it is desired to close and latch the door, it is merely necessary to swing the door into closed position as the inner side of the door will contact with the projection 14, and will rock the weight and all the associated parts into the position shown in Figure 1 in an automatic manner, thus again locking the door without necessitating the manipulation of the latch.

It will thus be seen that a very simple and attractive form of mail box has been provided which may be readily opened by a simple manipulation of the latching means, and which will automatically latch itself when the door is closed, without the use of any springs, cams, sliding members, or similar parts. When it is considered that these mail boxes stand out in the weather throughout the entire year, it is readily appreciated that this simple and effective construction is

eminently suited to such use and materially simplifies and advances the art of mail box construction.

Although the invention has been described in considerable detail, it is to be understood that the invention may be variously embodied and is, therefore, to be limited only as claimed.

I claim:

10 A mail box comprising a body portion, a door closing one end thereof and pivoted adjacent its lower end to said body portion, a latch pivoted to the upper forward part of said body portion, and having a weighted 15 handle and an inwardly directed latching tongue adapted to be positioned in front of

said door when said door is closed, said latch having an arm extending inwardly of said box and provided with a projecting member adapted to contact with the inner side of 20 said door when said latch is rocked rearwardly to thus throw said door open, said weight being so related to the pivot point of said latch as to occupy positions on opposite sides of said pivot point when said latch is 25 in its locking and unlocking position.

In testimony that I claim the foregoing I have hereunto set my hand at Sheboygan, in the county of Sheboygan and State of Wisconsin.

FERDINAND SCHWARZ.
